UNITED STATES PATENT OFFICE.

MAX BOREMSKY, OF NEW YORK, N. Y.

DESIGN FOR A CIGAR.

SPECIFICATION forming part of Design No. 19,705, dated March 18, 1890.

Application filed February 5, 1890. Serial No. 339,347. Term of patent 3½ years.

To all whom it may concern:

Be it known that I, MAX BOREMSKY, of the the city, county, and State of New York, a citizen of the United States, have invented a 5 new and original Design for Cigars, of which the following is a specification.

In the accompanying drawing a side view of a cigar showing my design is shown.

The leading feature of my design consists 10 in a groove extending around the cigar a short distance from the pointed end or tip.

A is the cigar. B is a groove extending around the same a short distance from the pointed end or tip. C is an acorn-shaped 15 head at one side of said groove B.

Having thus described my design, what I claim is—

A design for a cigar, consisting of an annular groove extending around the cigar a short distance from the pointed end, and an 2c acorn-shaped tip on the end of the cigar adjacent to said groove, substantially as set forth.

In testimony that I claim the foregoing as my invention I have signed my name in presence of two subscribing witnesses.

MAX BOREMSKY.
